WOLFGANG E. SCHWARZMANN, OF LONGMEADOW, AND ADOLPH ROSNER, OF SPRINGFIELD, MASSACHUSETTS, ASSIGNORS, BY MESNE ASSIGNMENTS, TO THE ELECTRIC AUTO-LITE COMPANY, A CORPORATION OF OHIO

CABLE TERMINAL

Application filed July 29, 1921. Serial No. 488,304.

The present invention relates to connectors for electrical cables, such as those used in ignition systems for internal combustion engines.

Heretofore, the plug member of a plug and socket type of cable connector, has been made with inwardly projecting pieces that extended transversely into the insulating covering of the cable. It was necessary, in such member, to manually attach it to the end of the cable by first spreading the side portions of the member sufficiently to permit the insertion of the cable and then to forcibly cause the lateral extensions to enter the insulation. 5 When shipping instruments or apparatus using such members, the same, if placed in their respective sockets, had to be withdrawn from such sockets at the time of attaching these members to the cable ends and accordingly, 10 could not be attached to the cable ends while in such sockets.

In accordance with this part of the invention, we form the plug member with a plurality of inwardly projecting and downwardly extending prongs which permit the ready insertion of the end of the cable in the plug member, but becomes fixed to the cable when it is moved in the opposite direction, thus preventing the withdrawal of the cable from the 15 plug member, the prongs digging into the cable covering for such purpose. It will be thus apparent that when the cable is withdrawn from the socket member, the plug member will be withdrawn therefrom as a unitary 20 part of the cable. In order to give stiffness to the prongs and to reduce the amount of material required for a plug member of a given length, the prongs are preferably located intermediate the ends of the plug member, 25 while the latter may also have at its lower end an inwardly extending projection adapted to enter into the electrically conductive part of the cable when the latter is inserted into the plug member.

Referring more particularly to the accompanying drawing, upon which are shown a few embodiments of the invention, in application, as for example, to a distributor head and spark plugs of an ignition system for 30 internal combustion engines:

Fig. 1 is a vertical sectional view of a distributor head showing the connectors in connected position; Fig. 2 is a side view in elevation of the plug portion of the connector, with the cable-end in place therein; Fig. 3 is a longitudinal sectional view of the same taken on line 3—3 of Fig. 5; Fig. 4 is a developed plan view of the plug member; Fig. 5 is a bottom plan view of the plug member with the cable end in place; Fig. 6 is a transverse sectional view taken on line 6—6 of Fig. 3; Fig. 7 is a longitudinal sectional view of the plug member per se.

The connector constructed in accordance with the invention is shown in Fig. 1 in connection with a distributor head 1 in which normally operates or rotates a rotor 2 carrying a radially extending brush insert member 3 successively cooperative with the lower terminals 4 of the inserts 5 molded in the 55 head 1, the lower terminals being formed integral with the socket members 6 embedded in the posts or towers 7 from which lead the high tension leads 8 to the respective spark plugs in the engine cylinders. In the center of the 60 head 1 is provided a central tower or post 9 having a metal insert 10 recessed at its lower end to receive a contact brush member 11 cooperative with the inner end of the brush 3 in a known manner, and provided at its 65 other end with the socket member 12, similar to socket 5, for receiving the end of a high tension lead or cable 13 extending to the secondary winding of an induction coil or magneto armature.

The connector comprises, in general, a socket member, such as the member 6, and a plug member 14. The latter is constructed from a sheet metal punching, shown in developed plan form in Fig. 4 of the drawing. 70 This punching or blank comprises, in general, a border portion 15 having a plurality of downwardly extending finger portions 16 and 17 arranged in spaced relation, two of these finger portions being connected together 75 by a transverse connecting member 18, thus rigidly maintaining the relation of the adjacent or connected fingers 17. Alternating with the fingers 16 and 17 are also provided downwardly extending sharpened portions 80

or prongs 19 which are bent inwardly and extend downwardly, as viewed in Figs. 1, 2, 3, 4 and 7 of the drawing, for a purpose herein-after more fully described. The connecting portion 18 is also provided with a downwardly extending portion 20 which may be suitably sharpened or pointed and bent to enter into the electrically conductive part of the cable, as will hereinafter more fully appear. 5

10 It will be observed that the portion 20 is located between and adjacent the fingers 17 and is sheared or slotted on the lines 21, in order that the member 20 may be readily shaped into the form shown in Fig. 3 of the drawing, when the punching or blank is rolled and shaped for connection with the end of the cable. The fingers are also preferably provided with widened portions 22, such that when bent on the lines 23, as shown in Fig. 15 20, the end portions 24 will extend inwardly in a transverse fashion at the end of the plug member, as is clearly shown in Figs. 2, 3, 5 and 7 of the drawing, and with the widened portions 22 located near each other, so that 25 the same may encase or surround the lower end of the cable, particularly the cover thereon, so as to prevent the upward projection of the frayed ends of the braided threads of the cable sheathing. 30

35 The punching or blank is rolled into the form of a cylinder so that the ends 25 and 26 thereof will be located adjacent each other and the ends 24 bent inwardly as well as the end portion 20, the latter being bent about the lines 27 and 28, as shown in Fig. 4 of the drawing, thus forming a sort of U-shaped member or hook with the point 29 thereof extending inwardly and upwardly within the interior of the plug member. With the member in the form above described, it will be 40 noted that the prongs 19 extend inwardly and downwardly, so that when the end of the cable is inserted or forced into the plug member, the insulating covering of the cable will be 45 permitted to pass by the ends of the prongs 19, but any tendency to withdraw the cable will cause the prongs 19 to be forced inwardly into the insulating cover, thus preventing the cable from becoming detached from the plug member, the latter thus becoming 50 fixed to and forming a unitary part of the end of the cable. It will be also observed that when the end of the cable is inserted in the plug member, the point 29 of the member 20 is located centrally, so that it will be forced 55 inwardly into or among the wires of a conducting portion of the cable. The member 20 may be caused to bend as the end of the cable is forced onto or over the point 29, and therefore, for the purpose of preventing total 60 deformation of the member 20, the end portions 30 of the fingers 17 are so bent and cut that they will over-lap the member 20 at the lower end of the plug shell, as is clearly 65 shown in Figs. 3 and 5 of the drawing. As

the member 20 is forced downwardly, it will contact with the over-lapping portions 31 of the portions 30, such over-lapping portions accordingly acting as an abutment means for the member 20 to prevent further bending thereof, as the end of the cable is forced into the plug member. A slight backward pull of the cable will cause the prongs to dig in firmly into the insulating covering of the cable, and also permit the member 20 to return to normal shape, such as is shown in Fig. 3 of the drawing. 70

75 The spring fingers 16 and 17 are also further outwardly bent to form groove engaging positions 32, which are adapted, when the plug member is inserted in the socket, to snap into or engage in an internal annular groove 33 formed in the socket member 5. The fingers 16 and 17 will radially flex inwardly when the plug member is inserted in the socket 80 member until the bent portions 32 arrive opposite the groove 33 and resiliently snap thereinto, such bent portions acting to normally hold or maintain the plug member and the attached cable within said socket, yet 85 permitting the unitary detachment thereof by a strong manual pull of the cable. 90

95 It will be observed that the type of connector above described is not limited to use in any particular device, such as a distributor 100 head, but may also be connected to various other devices, such as spark plugs and the like.

105 The end of the cable is merely cut without further trimming or other preparation for 100 connection to the connector. It is merely necessary to transversely cut the cable and then insert the cut end thereof into the plug member. In the manufacture of electrical equipment, such as that used in ignition systems, it is customary to ship the same with 105 the connector members, particularly the part to be eventually attached to the cable, tied to the instrument with a piece of wire or cord. When installing the same, the connector member must then be attached to the cable. This 110 inconvenience is avoided by the present invention by inserting the plug member into the sockets of the distributor, at the time of shipment, and when the apparatus is later installed, it is merely necessary to cut a cable to suitable length and insert the cut end thereof into the plug member while it is still in its socket. As the end of the cable is forced 115 inwardly into the plug member, it will pass by the prongs 19 and engage with the point 29 so as to establish electrical connection between the latter and the electrical conductive part of the cable. An opposite pull upon the cable 120 will cause the prongs to dig into the insulation of the cable and fix the plug member to the end of the cable, so that further withdrawal action on the cable will cause the same 125 to draw the plug member with it as a unitary 130

part thereof, the spring fingers 16 and 17 readily flexing for that purpose.

We claim:

1. A socket fitting plug adapted to be attached to the end of an electric cable, comprising a tubular body portion having an open end adapted to receive the end of the cable, the sides of said body portion being adapted to snugly fit the sides of the cable; a prong integral with said tubular body portion, forming in part the closure for the opposite end thereof and adapted to enter the conducting portion of said cable as said cable is inserted into said body portion; means to reinforce said prong against distortion when said cable is so inserted; and means integral with the sides of said body portion adapted to close in upon said cable to prevent the removal of said cable when such removal is attempted.

2. An electric cable connector; a plug member adapted to fit into a socket member, the plug member made of sheet material and adapted to be attached to the end of an electric cable comprising: a tubular portion; a plurality of finger portions extending therefrom in spaced relation; an extending prong connecting two of said finger portions adapted to be bent forming part of the closure for the end of the cable and arranged to enter the conducting portion of said cable when said cable is inserted; a plurality of inwardly projecting prongs alternately extending from said tubular portion with respect to said fingers and arranged to permit the insertion of the end of said cable and become fixed thereto.

3. An electric cable connector; a plug member adapted to fit into a socket member, the plug member made of sheet material and adapted to be attached to the end of an electric cable comprising: a tubular portion; a plurality of spaced fingers; a plurality of cable holding prongs between said fingers, the finger ends being enlarged transversely and tapered to a point; a bridge connecting two fingers and a piercing point extending from said bridge and adapted to enter the conducting portion of the cable when said cable is inserted in said plug.

50 In testimony whereof I affix my signature.

ADOLPH ROSNER.

In testimony whereof I affix my signature.

WOLFGANG E. SCHWARZMANN.
